APPARATUS FOR MAKING HAND KNITTED GARMENTS

Juan Manuel de la Peña, Mexico City, Mexico

Application October 30, 1942, Serial No. 463,928
In Mexico March 12, 1942

2 Claims. (Cl. 66—4)

Hand operated knitting apparatus have of course suffered accidental damages, especially of the needles, and often it is convenient to be enabled to remove for instance every second slid-able needle, in order to operate the apparatus for certain class of knitting, but such removing and replacing of needles have required expert mech-anical help.

This invention relates to an improved construction of slidable needles, and the manner of in-suring a rapid removal and replacing of the needles, at home by the lady knitter.

In the drawing

Fig. 1 is a perspective view of the apparatus.

Fig. 2 a side view of the needle guide board.

Fig. 3 a perspective view of a removable bar with double hooked needles.

Fig. 4 a top view detail showing slidable needles in extended position.

Fig. 5 a top view showing the slidable needles in withdrawn position, after making the inter-locking loops.

On a frame 1 is mounted a needle guide board 2 of sheet metal, with an upstanding front edge 3 turned over to form a channeled flange 4, and a back edge 5 folded over into a raised hem 6.

The front edge has therein a row of perforations 7, and the hem 6 a row of grooves 8, for the in-ser-tion of needles 9, each of which is formed alike of a length of metal wire or rod bent at one end to form a knee 10, and also intermediately to form a heel 11 which merges rearwardly into a straight extension 12. The front ends of the needles with the knees traverse the perforations 7, while the heels 11 are guided in slots 13 in the guide board 2, while the extensions 12 slidably rest in the grooves 8.

When all needles are assembled as explained, a locking wire 14 is inserted into the hem 6 from one end above the extensions 12, so that they are held within their grooves. The needles are inter-changeable by pulling out the wire 14.

A removable bar 15 with double hooked needles 16 is mounted in front of the support 1 and is held at its ends in slots 17 in brackets 18 which are clamped to the frame 1 by means of bolts with wing nuts 19. The bolts traverse a slot in each bracket whereby the brackets can be adjusted to locate the bar 15 at a variable spacing from the edge 3.

The distance between the rows of needles 9 and 16 is thus made adjustable, and spacing buffers 20, only one of which is shown, are mounted on the front wall 21 of the frame 1 between said wall and the bar 15, said buffers being adjustable hori-zontally on the frame in any suitable manner, by means not shown.

After making loops 19 on so many needles 16 as the starting width of garment piece requires, a 60

corresponding number of slidable needles 9 are pushed forward between the stationary needles 16, thereupon the yarn 20 is laid transversely over the horizontal extensions 21 of the needles 9, be-tween the upstanding ends of said needles and the hooked needles 16. An actuating ruler 22 with wedge shaped ends 23 is then pushed under the extensions 21, one of said ends pushing on the heels 11 to draw the needles 9 inwardly forming an interlocking chain 24. The loops on the needles 16 are then lifted over the double hooks, the bar 15 is removed from the grooves 17, and after being turned with the opposite side toward the needles 9, it is again affixed between the brackets so that a following row of loops may be made.

The loops 19 are required only at the beginning of knitting. They are lifted over the double hooks of the needles 16 by means of a known comb with teeth spaced exactly as the needles 16, so that each comb tooth will catch in a longitudinal groove in the front of the needle and slide up under a corresponding loop 19 making it possible with one single tipping movement of the comb to simulta-neously slip all of the loops 19 off their needles 16. The bar 15 is now removed from the grooves 17, and by so removing the bar 15, the interlocking chain naturally is released from the needles 9. After turning the bar 15 with the opposite side toward the needles 9, it is again mounted in the grooves 17, so that a following row of loops may be made.

The bar 15 is removed so as to slip off all the loops of the interlocking chain 24 from the needles 9, and the bar 15 is turned so as to bring the work toward the operator after the work has been passed over the needles 16.

The second row of loops is formed by folding the loops on the needles 16 over the end of the double hooks of these needles 16, either by means 40 of a comb or simply by folding over the work. By lifting the bar 15 the interlocking chain 24 is forced to slip off the needles 9.

I claim:

1. An apparatus for hand knitting, comprising a needle guide board with a raised front edge pro-vided with a row of perforations, and a raised back end formed into a hem provided with grooves, slots in the guide board and a number of remov-able needles having heels guided in said slots, one end of a needle being inserted in one of said perforations, and the other in one of said grooves, and a locking wire in said hem on top of said needle ends.

2. An apparatus for hand knitting according to claim 1, comprising an adjustable spacing buffer between the needle guide board and an adjustable removable bar carrying hooked needles.
